TERMINAL CONNECTION FOR ELECTRIC LAMP SOCKETS

Filed March 1, 1930

UNITED STATES PATENT OFFICE

ISRAEL H. SHALOMITH, OF BROOKLYN, NEW YORK, ASSIGNOR OF ONE-HALF TO IRA F. DASH, OF NEW YORK, N. Y.

TERMINAL CONNECTION FOR ELECTRIC LAMP SOCKETS

Application filed March 1, 1930. Serial No. 432,353.

This invention relates to electric lamp sockets and more particularly is directed to improved solderless terminal attachment means for connecting flexible conductor wires to the current carrying parts of a lamp socket.

One object of the invention is to provide lamp socket constructions having an improved solderless attachment means of the character described which shall permit economic quantity assembly production of lamp sockets to form portable decorative lighting sets, such as Christmas tree lighting outfits, and which shall reduce to a minimum the skill required in assembling of such outfits and at the same time eliminates possible fire and accident hazards usually present in soldered operations.

Another object of the invention is to provide an improved solderless terminal attachment means for connecting flexible conductor wires to the current carrying parts of lamp sockets comprising few and simple parts forming a rugged assembly which shall be cheap to manufacture, and practical and efficient to a high degree in use.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention.

Fig. 1 is a front elevational view, in section, showing an electric lamp socket, such as used in Christmas tree lighting outfits provided with a solderless terminal attachment means for connecting flexible conductor wires to the current carrying parts of the lamp socket embodying the invention.

Figs. 2, 3 and 4 are cross-sectional views corresponding to cuts taken on lines 2-2, 3-3 and 4-4, respectively, in Fig. 1.

Fig. 5 is a fragmentary cross-sectional view taken on line 5-5 in Fig. 3.

Fig. 6 is a perspective view of the screw shell and center contact portions attached to the flexible conductor wires removed from the socket casing, said portions being in separated position ready for assembly.

Fig. 7 is a perspective view showing the improved center contact portion removed from the socket connected to braided insulated conductor wire, and

Fig. 8 is a cross-sectional view taken on line 8-8 in Fig. 7.

Referring in detail to the drawing, 10 denotes an electric lamp socket constructed to embody the invention. Said socket is seen to include improved solderless terminal attachment means for connecting flexible conductor wires 11 and 12 to the terminals 13 and 14, respectively of the current carrying parts, namely the screw shell and center contact portions 15 and 16, respectively, of the lamp socket. Said conductor wires 11 and 12 are preferably formed with cores or strands 11a and 12a, respectively, having suitable insulating covering 11b and 12b, respectively, of any well understood construction.

The socket 10 may be of the miniature type, adapted to be connected in either series or parallel circuit with other sockets in forming a Christmas tree lighting outfit. Only a fragmentary portion of such an outfit is here shown, in which the socket 10 comprises a molded insulating casing 17 having a chamber 17a extending in from the open or top end 17b thereof. Said casing is formed with an end wall 17c at the bottom of the chamber 17a provided with a central passage 17d where-through the conductor wires 11 and 12 extend as is clearly shown in Figs. 1 and 3.

Snugly fitted into the chamber 17a is metallic screw shell contact portion 15 which is adapted to receive the base of a miniature lamp, indicated at L in dotted lines. The shell contact portion 15 at its inner end, has an inturned flange 15a which supports an insulated disc or washer 18. Said washer carries the center contact portion 16 which is in the form of an eyelet rivet. Any suitable means may be provided for anchoring the shell contact portion 15 within the casing as

for example, friction ribs 17e parallelly spaced along the walls of the chamber 17a.

The terminal 13 provided on the shell contact portion 15 comprises a resilient tab which preferably is formed integral with the flange 15a and is adapted to be bent back against the outer surface of the shell contact portion 15 to provide a loop bight at 19 for engaging with the bared strands 11a of the conductor wire 11. The terminal tab 13 may be notched and shaped at 13a adjacent the bight 19 to provide an efficient electrical connection for the conductor strands 11a with the shell contact portion 15 and to avoid any possibility of said strands being cut by the sharp edges in the manner clearly seen from Fig. 5. With the current carrying parts assembled within the casing 17, as shown in Fig. 1, the conductor strands 11a are tightly wedged between the tab 13 and the outside of the contact shell portion 15, thus providing not only the good electrical connection, but also a highly efficient mechanical attachment.

The center contact portion or eyelet rivet 16, has its shank portion 16a inserted through an opening 12a pierced through the conductor wire 12 midway between the strands 12a so that said shank 16b contacts said strands 12a as shown in Fig. 4. The head or top end of 16b of said rivet 16 is adapted to contact with the base of the lamp and the bottom end of the eyelet rivet extending beyond the washer 18 and conductor strands 12a is split at 16d to provide oppositely extending clamping lugs, forming the terminals 14.

Where the insulation covering 12b is rubber, the lugs 14 when pressed down in clamping position, as shown in Fig. 4, will sever said covering and tightly contact with the strands 12a.

The practical application of the invention will now be apparent. The conductor wires 11, after being bared to expose the strands 11a are inserted in the loop bight 19 formed between the tab 13 and the shell contact portion 15. The conductor wire 12 is inserted up through the shell contact portion and electrically and mechanically connected to the terminal 14 of the eyelet rivet 16 in the manner described above and as shown in Fig. 6. The current carrying parts are then forced down into the chamber casing 17a where they are rigidly retained against accidental movement. The assembly of the current carrying parts within the casing tightly clamps the conductor strands 11a to the terminal 13 while the terminal 14 of eyelet rivet 16 anchors the conductor strands 12a. The rim 17f of the casing opening 17d may be extended and a suitable insulating sealing compound 20 confined within said rim about the conductor wires 11 and 12 for weather proofing the socket and for anchoring said wires to prevent possible relative movement between the

wires and the current carrying parts. It is thus seen that the entire assembly and solderless connections are made with a minimum degree of skill while all possible fire and accident hazards usually present in soldering operations are here eliminated.

In Figs. 7 and 8 connection for conductor wire 112 having a braided insulating covering 112b is shown, instead of rubber as described above. Here the rivet 16 through the terminals 14 firmly clamp the conductor wires 112 and contact with the strands 112a although the lug terminals 14 do not sever the braid covering 112b as when rubber insulated conductor wires are used. It should be noted that the conductor wires 12 and 112 are completely insulated by the coverings 12b and 112b, respectively, up to the terminals 14, so that any possibility of accidental short circuit within the socket is avoided, and since no soldering is required in the above described improved constructions, other short circuits due to the use of soldering flux is also eliminated.

It will thus be seen that there is provided a lamp socket in which the several objects of this invention are achieved and which are well adapted to meet the conditions of practical use.

As various possible embodiments might be made of the above invention, and as various changes might be made in the embodiment above set forth, it is to be understood that all matters herein set forth or shown in the accompanying drawing are to be interpreted as illustrative and not in a limiting sense.

Having thus described my invention, I claim as new and desire to secure by Letters Patent:

1. In an electric lamp socket, solderless attachment means for connecting stranded core conductor wires to current carrying parts of the socket comprising an eyelet rivet having a split end forming lug terminals for clampingly engaging separated portions of the conductor wires stranded core to the rivet.

2. In an electric lamp socket, a center contact portion comprising an eyelet rivet, a solderless attachment means formed from a split end of said rivet for connecting a flexible wire thereto, said split end being bent to provide a lug terminal extending transverse the wire for clampingly engaging and securing the latter to the rivet.

3. In an electric lamp socket, a center contact portion comprising an eyelet rivet having a solderless lug terminal formed from a split end of said rivet, said split end being adapted to extend through the insulated covering of a stranded wire and between separate core portions of the wire strands and bent to clampingly engage the same.

4. In an electric socket having an insulated casing, a screw shell contact portion, a resili-

ent tab terminal, extending from said portion bent to form a loop for receiving a wire adapted to clampingly retain the latter when assembled in the socket casing, an eyelet rivet

5 formed with a split end, said split end being bent to provide a lug terminal extending transverse another wire for clampingly engaging and securing the latter to the rivet.

5. In an electric lamp socket having an 10 insulating casing, a screw shell contact portion formed with an inturned flange at one end thereof, a resilient tab terminal extending from said flange, said terminal being bent to provide a loop adapted to receive a conductor wire for clampingly retaining the latter when assembled in the socket casing, an eyelet rivet having a solderless lug terminal formed from a split end of said rivet, said split end being adapted to extend through 15 20 the insulated covering of a stranded wire and between separate core portions of the wire strands and bent to clampingly engage the same.

In testimony whereof I affix my signature.
25 ISRAEL H. SHALOMITH.
